US0D1071818S

(12) **United States Design Patent** (10) Patent No.: **US D1,071,818 S**
(45) Date of Patent: ** Apr. 22, 2025

(54) **VEHICLE SIDE STEP**

(71) Applicant: **Ford Global Technologies, LLC**,
Dearborn, MI (US)

(72) Inventors: **Todd Willing**, Grosse Pointe, MI (US);
Max Wolff, Elsternwick (AU); **Max Tran**, Pascoe Vale (AU); **Leigh H. Cosentino**, Seddon (AU); **Tae Hoon Kang**, Essendon (AU)

(73) Assignee: **Ford Global Technologies, LLC**,
Dearborn, MI (US)

(**) Term: **15 Years**

(21) Appl. No.: **29/805,342**

(22) Filed: **Aug. 26, 2021**

(51) LOC (15) Cl. **12-16**
(52) U.S. Cl.
USPC **D12/203**

(58) **Field of Classification Search**

USPC D12/203, 196, 190, 162, 98, 93, 86
CPC .. B60R 3/02; B60R 3/00; B60R 3/002; B60R
3/005; B60R 3/007

(57) **CLAIM**

The ornamental design for a vehicle side step as shown and described.

DESCRIPTION

FIG. 1 is a front elevational view of a vehicle side step, showing our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a bottom, front and right side perspective view thereof; and,

FIG. 7 is a top, front and right side perspective view thereof. The claimed design is indicated by the relatively dark portions in the figures. The de-emphasized and relatively light portions form no part of the claimed design.

1 Claim, 7 Drawing Sheets
